Patented May 10, 1966

204,671

MARINER'S KNIFE

Harry K. McEvoy, 2110 Tremont Blvd. NW,
Grand Rapids, Mich.

Filed Aug. 26, 1964, Ser. No. 81,455

Term of patent 14 years

(Cl. D22—3)

Fig. 1.

Fig. 2.

Fig. 3.

I claim:

The ornamental design for a mariner's knife, as shown.
